EYEGLASS CONSTRUCTION

Axel Person, Attleboro, Mass., assignor to Bay State Optical Company, Attleboro, Mass., a corporation of Maine

Application November 25, 1940, Serial No. 366,964

4 Claims. (Cl. 88—53)

This invention relates to a non-metallic eyeglass frame construction.

One of the objects of this invention is to provide an eyeglass construction which will be sturdy and well able to withstand hard usage. Another object is to provide a construction of the above character which may be manufactured from light and inexpensive materials. Another object is to provide a construction of the above character which is simple, thoroughly practical, and durable in use. A still further object is to provide a construction of the above character which will be especially strong in certain vulnerable spots of the above type of construction. Another object is to provide an eyeglass construction of the above character which will be neat and attractive in appearance. A further object is to provide a construction of the above character wherein the metallic parts are reliably secured to the plastic material. A still further object is to provide a construction of the above character wherein the metallic parts are concealed to a great extent to give a pleasing effect. Other objects will be in part obvious and in part pointed out hereinafter.

The invention accordingly consists in the features of construction, combinations of elements and arrangements of parts, all as will be illustratively described herein, and the scope of the application of which will be indicated in the following claims.

In the accompanying drawing in which is shown one of the various possible embodiments of my invention,

Figure 1 is a side elevation of an eyeglass frame having the features of my invention embodied therein;

Figure 2 is a vertical sectional view, on an enlarged scale, of a portion of the frame shown in Figure 1 prior to assembly;

Figure 3 is a perspective view, on an enlarged scale, of an insert which becomes a portion of the frame during assembly;

Figure 4 is a perspective view, on an enlarged scale, of a metallic fitting used in the frame;

Figure 5 is a perspective view, on an enlarged scale, showing the parts of Figures 3 and 4 in assembled relationship; and,

Figure 6 is a top plan view, on an enlarged scale, of a portion of the frame shown in Figure 1.

Similar reference characters refer to similar parts throughout the several views of the drawing.

As conducive to a clearer understanding of certain features of this invention, it might here be pointed out that it has been found desirable to use metallic parts to perform certain functions in non-metallic frames. This need arises from the fact that the non-metallic material used in eyeglass frames has not sufficient strength to

perform certain functions—for example, it has not the strength to make a strong and durable hinge. In the past, the metallic parts used to perform these functions have been bulky, and this fact has materially detracted from the appearance of non-metallic frames. Furthermore, difficulty has been experienced in obtaining a strong and durable connection between a metallic part and a non-metallic frame which is able to withstand the strain of extensive use. It is, accordingly, another object of this invention to overcome the above-mentioned difficulties, as well as many others.

It might here be noted that reference herein after to an "outward" direction signifies a direction to the left or right of the bridge of an eyeglass frame in the direction of the temples, while the term "inward" denotes a direction opposite thereto. A "rearward" direction refers to a direction toward the face of the wearer, whereas the term "forward" denotes the opposite direction. An "upward" direction refers to a direction upwardly from the face of the wearer, while a "downward" direction is opposite thereto.

Referring now to the drawing in detail, in Figure 1 there is shown an eyeglass frame in side elevation made of zylonite or like material. This frame includes a rim 10, a nose guard 11, and a bridge 12, and has a rearwardly curved endpiece, generally indicated at 13, formed thereon (Figure 6). This endpiece is preferably integral with rim 10 and is hingedly connected to a temple 15 by a metallic fitting, generally indicated at 14, mounted in the end piece.

In Figure 2, endpiece 13 is shown before the insertion of metallic fitting 14. At this stage of assembly, the endpiece has a slot 16 cut therein which is in substantially a horizontal plane with respect to the normal position of the frame when worn. This slot is of substantially uniform thickness and separates endpiece 13 into two tongue portions 17 and 18.

Metallic fitting 14 (Figure 4) is preferably stamped from sheet metal of a thickness substantially equal to the width of endpiece slot 16 and comprises an elongated curved section 25, which has an eye 19 formed on its outer end and a rearwardly extending projection 20 (Figure 6) formed on its inner end. This projection extends a substantial distance outwardly from the side of curved section 25 transversely of endpiece 13, forming a hook-shaped end on the fitting.

To connect fitting 14 to endpiece 13, it is first mounted in a plastic insert 22 (Figure 3). This insert is preferably cut from a sheet of plastic material, such as zylonite, and has substantially the same thickness as metallic fitting 14. An opening 21 is formed in the center portion of this insert (Figure 3) and extends vertically

therethrough. This opening is of substantially the same shape as and is adapted to snugly receive metallic fitting 14 (Figure 5). Thus, when fitting 14 is positioned in opening 21, the two form a flat member having a thickness substantially equal to the width of slot 16.

After the insertion of fitting 14 into opening 21, the upper and lower surfaces of the fitting and the insert are coated with a priming lacquer having a cellulose base. This lacquer is allowed to dry, and then a cellulose solvent, such as ethyl acetate, is applied to the upper and lower surfaces of the fitting and insert and also to the sides of slot 16 in endpiece 13. When this solvent reduces the lacquer and the zylonite surfaces to which it was applied to a fusible state, insert 22 and fitting 14 are placed between tongues 17 and 18 (Figure 2) of endpiece 13. Fitting 14 is so positioned that its elongated curved section 25 (Figure 6) extends through the center portion of the endpiece with projection 20 positioned at the inner end of the slot and eye 19 extending rearwardly from the rear end thereof.

When fitting 14 is so positioned, tongues 17 and 18 are pressed toward each other so that they bear upon the upper and lower surfaces of fitting 14 and insert 22. This forces the solvent coated surfaces into contact with each other, and then, as the solvent evaporates, these surfaces fuse together to form a strong and durable joint. Thus, insert 22 becomes in effect an integral part of the endpiece, and fitting 14 is securely connected to tongues 17 and 18 by the fusing of the tongues to the layer of lacquer covering the fitting.

When the connection is completed, the zylonite of insert 22, protruding from slot 16, is trimmed to the shape of endpiece 13 which exposes ear 19. Temple 15 (Figures 1 and 6) has a temple fitting 26 secured to its center rod 24, and this fitting has a pair of ears, one of which is shown at 27, formed thereon. Ear 19 is adapted to fit between these ears, and a screw 23 is passed through them to form a hinged connection between the temple and part 14. Ear 19 and the ears of fitting 26 are so positioned that the axis of screw 23 is in substantial alignment with the right side of temple 15, as viewed in Figure 6. Thus, movement of temple 15 in an outer direction is limited by the outer portion of fitting 26 abutting against the end of endpiece 13 and an abutment 28 formed on fitting 14 (Figures 4 and 6).

It will thus be seen that a practical and durable joint between metallic fitting 14 and endpiece 13 is disclosed. This results both from the manner in which fitting 14 is mounted in endpiece 13 and from the shape of the fitting. Thus, projection 20, which extends a substantial distance into the endpiece transversely thereof, securely anchors the fitting therein so that it firmly resists all strains resulting from use. Furthermore, fitting 14 is mounted in the endpiece in a manner that prevents the formation of internal strains in the endpiece during the connection of the metallic fitting thereto.

It will thus be seen that I have provided a thoroughly practical and efficient construction in which the several objects hereinabove referred to, as well as many others, are successfully accomplished.

As many possible embodiments may be made

of the mechanical features of the above invention, and as many changes might be made in the embodiment above set forth, it is to be understood that all matter hereinabove set forth, or shown in the accompanying drawing, is to be interpreted as illustrative and not in a limiting sense.

I claim:

1. In eyeglass construction, in combination, a pair of non-metallic rims, bridge means connecting said rims, said rims having a pair of slots formed therein, a pair of non-metallic members, said non-metallic members being of a width substantially equal to the width of said slots and having preformed holes therein, a pair of metallic fittings fitted into said preformed holes, a cement securing said non-metallic members in said slots, and a pair of temples secured to said metallic fittings.

2. In eyeglass construction, in combination, a pair of non-metallic rim members, bridge means connecting said rim members, said rim members having a pair of slots formed therein, a pair of inserts of non-metallic material, a pair of flat metallic fittings, said metallic fittings having projections formed thereon extending outwardly from the edges thereof a substantial distance, said inserts having openings formed therein of the same shape as said metallic fittings and said metallic fittings being positioned in said openings, a cement securing said inserts in said slots, and a pair of temples secured to said metallic fittings.

3. In eyeglass construction, in combination, a pair of plastic rim members, bridge means connecting said rim members, a pair of rearwardly curved endpieces formed on said rim members, said endpieces having a pair of slots formed therein extending in substantially a horizontal plane with respect to the normal position of the frame when worn, a pair of flat plastic inserts having substantially the same thickness as said slots having openings formed therein, a pair of flat metallic fittings of substantially the same thickness as said inserts, projections of substantial size formed on said metallic fittings and extending outwardly from the edges thereof, said metallic fittings being fitted into the openings in said plastic inserts, a cement securing said inserts and said metallic fittings to the side walls of said slots, and a pair of temples secured to said fittings.

4. In eyeglass construction, in combination, a pair of rim members having non-metallic endpieces formed thereon, bridge means connecting said rim members, said endpieces having a pair of slots formed therein extending in substantially a horizontal plane with respect to the normal position of the frame when worn, a pair of flat plastic inserts having substantially the same thickness as said slots and having preformed holes formed therein, a pair of flat metallic fittings of substantially the same thickness as said slots, a projection extending rearwardly from the inner end of each of said fittings to form a hook-shaped end thereon, said metallic fittings fitting into the preformed holes in said plastic inserts, a cement securing said inserts to the side walls of said slot, and a pair of temples secured to said fittings.

AXEL PERSON.
